US00D948019S

(12) **United States Design Patent** (10) Patent No.: **US D948,019 S**
Kim (45) Date of Patent: ** Apr. 5, 2022

(54) **AIR PURIFIER**

(71) Applicant: **Easyrental Co., Ltd.**, Seoul (KR)

(72) Inventor: **Jong Man Kim**, Seoul (KR)

(**) Term: **15 Years**

(21) Appl. No.: **35/510,572**

(22) Filed: **Apr. 16, 2020**

(80) **Hague Agreement Data**

Int. Filing Date: **Apr. 16, 2020**

Int. Reg. No.: **DM/210445**

Int. Reg. Date: **Apr. 16, 2020**

Int. Reg. Pub. Date: **Oct. 16, 2020**

(30) **Foreign Application Priority Data**

Oct. 16, 2019 (KR) 30-2019-0049290

(51) **LOC (13) Cl.** **23-04**

(52) **U.S. Cl.**

USPC **D23/364**

(58) **Field of Classification Search**

USPC D23/355, 356, 359, 364, 370, 386

CPC B01D 46/00; B01D 46/0002; A61L 9/00
